UNITED STATES PATENT OFFICE.

JOHN M. FITZ GERALD, OF CHICAGO, ILLINOIS.

CONDUIT FASTENER.

1,418,370.

Specification of Letters Patent. Patented June 6, 1922.

Application filed August 15, 1917. Serial No. 186,261.

To all whom it may concern:

Be it known that I, JOHN M. FITZ GERALD, a citizen of the United States, residing at Chicago, in the county of Cook and State of Illinois, have invented a certain new and useful Improvement in Conduit Fasteners, of which the following is a full, clear, concise, and exact description.

This invention relates to improvements in electric cable conduits and more particularly to fastening means for the capping thereof.

In railway signalling systems, it is customary to house the electrical conductors thereof in suitable conduits. These conduits, as now constructed, comprise a long wooden box or trough, commonly referred to as the trunking, through which the conductors are passed, said trunking being open at the top thereof throughout its entire length in order that the conductors may be readily positioned therein after which a suitable capping which forms a cover for the trunk member is applied thereto. The capping is generally in the form of long strips or pieces of wood which extend longitudinally of the trunk member or a plurality of short strips or pieces extending transversely thereof and secured thereto by nails, screws or other more or less permanent fastening devices. In this manner, a complete housing for the conductors is provided which affords them limited mechanical and electrical protection.

This fastening of the capping to the trunk member in a more or less permanent manner, as above pointed out, is however, open to serious objections, owing to the inaccessibility of the contents of the conduit after the capping thereof has been secured in place. It becomes necessary from time to time to lay new wires or conductors or replace old or defective ones which requires an expenditure of considerable time and labor in removing the capping, which removal oftentimes causes said capping to become split or otherwise broken owing to its having been more or less permanently secured in place and also due to the rusting off of the heads of the nails or other fastening devices which are used in securing said capping in position.

An important object of the present inven-

tion is therefore to provide a fastener for conduits of the type described which shall be simple in construction and operation, economical to manufacture and one which may be readily and quickly applied to the conduit without the aid of nails, screws or any other like fastening means, and one which, when applied, will securely clamp the capping in place.

Another object is to provide a fastener which may be easily and quickly removed at any time without injury to the conduit in order to permit of the capping thereof being raised from the trunk member for the purpose of placing other conductors therein.

A further object is to provide a fastener of the type described comprising a plurality of members, one of which is adapted to receive and support the wooden conduit while the other member thereof is adapted to embrace said first member and said conduit and to securely clamp the capping thereof in place, said embracing member being provided with means adapted to engage the sides of said first named member to thereby hold said members securely clamped about said conduit.

Other objects and advantages will be apparent from the following description taken in connection with the drawings wherein several embodiments of the invention are illustrated.

Fig. 1 is a top plan view of a conduit showing fasteners constructed in accordance with the present invention applied thereto.

Fig. 2 is an enlarged sectional view taken on the line 2—2 of Fig. 1.

Fig. 3 is a sectional view taken on the line 3—3 of Fig. 2.

Fig. 4 shows the clamping member of the fastener applied directly to the wooden conduit, the shoe being omitted, and

Fig. 5 is a top plan view of a slightly modified form of fastener.

Referring more in detail to the drawings, the wooden conduit is illustrated at 1 and is shown comprising the usual trunk member 2 which is provided, as above pointed out, with a capping 3. As is customary, the wooden conduit is preferably supported above the ground on suitable posts, such as shown at 4 in order to prevent undue de-

terioration thereof. As above pointed out, the trunk member 2 is adapted to receive a plurality of conductors which are positioned therein through the top of said trunk member, the capping 3 being then applied thereto to provide a housing for said conductors.

In the present invention instead of nailing or otherwise permanently securing the capping 3 to the trunk member 2, as has heretofore been the custom, said capping is removably secured thereto by a plurality of fasteners disposed at various intervals throughout the length of the conduit, it being preferred to provide one at each of the points where the ends of the longitudinally extending cover strips, which form the capping, abut.

Each fastener preferably comprises a supporting shoe or base member 5 adapted to be securely anchored by means of a screw 6, or other suitable fastening means, to one of the supporting posts 4, said shoe being provided with side walls 7 preferably vertically grooved as at 8 for the purpose hereinafter pointed out. The shoe 5 is adapted to receive the wooden conduit, substantially as shown, and in such manner that the capping 3 thereof extends slightly above the side walls 7. A clamping member is illustrated at 9 and is shown provided with a top wall 10 and side walls 11, said clamping member being adapted to embrace said shoe substantially as shown, and in such manner that the top wall 10 thereof will firmly engage the capping 3. Formed in the side walls 11 of the clamping member are outstanding housings 12 adapted to receive cams 13 which are pivoted to suitable pins 14 extending through said housings 12 and journaled in the opposite walls thereof. The side walls 11 of the clamping member are preferably constructed of sufficient length to extend well down over the sides of the shoe, substantially as shown, said cams being so mounted as to fall by gravity into engagement with the sides of said shoe when the clamping member is pushed down into position with its top wall 10 in firm engagement with the capping 3 of the conduit to thereby prevent an accidental displacement of said clamping member and said capping and to firmly clamp said capping in position.

As above pointed out, the shoe is preferably vertically grooved as illustrated at 8, said grooves being of substantially the same width as the cam surfaces of the cams 13 and being adapted to receive the same, whereby said clamping member is anchored against longitudinal displacement. The lower ends 60 of the cams 13 are preferably provided with finger grips 15 whereby said cams may be rocked out of engagement with the sides of the shoe, in order that the clamping member may be readily and quickly removed when 65 desired. The cam surfaces of the cams 13

may be serrated or toothed, if desired, as illustrated at 16 in order to provide means whereby a more secure engagement with the sides of the shoe may be effected and maintained. The cams 13 may be locked in engagement with the sides of the shoe 5 after the clamping member 9 has been pushed down over said shoe into operative position as shown in Fig. 2 by means of cotter pins 17, or any other suitable means, said pins 17 extending through the side walls of the housings 12 so as to engage the rear surfaces of the cams 13 after the same have firmly gripped the sides of the shoe 5 to thereby prevent said cams being accidentally rocked out of engagement therewith.

While it is preferred to provide grooves in the sides of the shoe 5 adapted to receive the cams 13 to thereby prevent longitudinal displacement of the clamping member, it is obvious that the fasteners may be used without such grooves.

In Fig. 4 one of the clamping members 9 is shown clamping the capping 3 to the trunk member by means of the engagement of the cams thereof directly with the sides of said trunk member, the shoe 5 being dispensed with. If desired, the sides of the trunk member 2 may be provided with grooves, substantially similar to the grooves provided in the side walls of the shoe 5 to prevent longitudinal displacement of the clamping member when the same is used to clamp the capping 3 in place without the aid of the shoe, although an effective engagement may be maintained without the aid of such grooves.

In Fig. 5 is illustrated a slightly modified form of the invention wherein a fastener adapted to be applied to a conduit at a point where the same turns at an angle is shown, said fastener comprising a shoe and clamping member which are applied to the conduit in substantially the same manner as hereinbefore described. Instead, however, of providing the clamping member shown in this form of the invention with a cam at each side thereof, only one cam is provided, it being pivotally mounted in a suitable housing in the short side wall of said clamping member, substantially as shown, and adapted for engagement with the corresponding side wall of the shoe to insure a firm clamping of the capping in place. It is obvious that with this angular form of clamping member, no grooves need be provided to prevent longitudinal displacement. It will be noted by referring to Fig. 5 that the form of fastener shown therein obviates the necessity of joining the ends of conduits disposed at an angle to each other, said fastener acting to form a housing for the conductors from the point where they leave the one conduit to the point where they enter the other. This overcomes the necessity of 120

mitering the trunking and capping and joining them together in order to provide a continuous housing for the conductors. While a right angle fastener has been shown 5 in Fig. 5, it is obvious that fasteners of any other desired angle may be provided to accommodate the various angles encountered in the laying of conduits.

Fasteners of the type illustrated in Fig. 2 10 may also be provided with only one cam, if desired, and at the same time provide effective means whereby the capping may be securely clamped in position.

While the fasteners have been herein described and illustrated as particularly adaptable for use in clamping the capping of conduits adapted to house the conductors of railway signaling systems in place, it is obvious that said fasteners may be used for 20 many other purposes and it is therefore not desired to limit their use to the particular application shown and described.

Many other changes in addition to those above pointed out may also be made in the 25 embodiments of the invention herein illustrated where not limited in the appended claims.

Having thus described my invention, what I claim as new and desire to secure by Letters Patent of the United States is:—

1. A fastener adapted to clamp the capping of a conduit to the trunk member thereof comprising a shoe adapted to receive said trunk member, a clamping member adapted 35 to embrace said shoe and to engage said capping to hold the latter in position on said trunk member, and means, interposed between the side walls of said shoe and the side walls of said clamping member and housed 40 by the latter for holding said parts securely in position.

2. A fastener of the type described, comprising a shoe, a clamping member adapted to embrace the same and provided with 45 pending side walls adapted to overlie the side walls of said shoe, and gravity actuated cams carried by the side walls of said clamping member and adapted to frictionally engage the side walls of said shoe when said 50 clamping member is moved into operative position thereon.

3. A fastener of the type described, comprising a shoe, a trunk member fitted therein, a capping for said trunk member, a 55 clamping member adapted to embrace said capping and said shoe, and means housed within said clamping member adapted for engagement with said shoe to retain said clamping member in operative position 60 thereon, whereby said capping is held firmly on said trunk member.

4. A fastener comprising a shoe adapted 65 to receive a conduit, a clamping member adapted to embrace said shoe and to engage the cover of said conduit, said clamping

member having side walls which overlie the side walls of said shoe, and gravity-actuated cams carried by the side walls of said clamping member and adapted for engagement with the side walls of said shoe to clamp 70 said cover in position.

5. A fastener comprising a shoe adapted to receive a container, a clamping member adapted to embrace said shoe and to engage the cover of said container, cams carried by 75 said clamping member adapted to rock by gravity into engagement with the sides of said shoe to thereby clamp said cover in position, and means to prevent the disengagement of said cams. 80

6. The combination with a conduit comprising a trunk member and a capping, of a shoe adapted to receive said trunk member, grooves in the sides of said shoe, a clamping member adapted to embrace said 85 shoe and said capping to hold the latter on said trunk member, and means carried by said clamping member adapted to project into the grooves in said shoe to thereby prevent accidental longitudinal displacement of 90 said clamping member.

7. A fastener of the type described, comprising a clamping member adapted to embrace a conduit to clamp the capping thereof in position and cams mounted within 95 said member and adapted to project inwardly into engagement with the sides of said conduit to thereby retain said member and said capping against accidental displacement. 100

8. A fastener of the type described, comprising a clamping member adapted to embrace a conduit to clamp the capping thereof in position, gravity actuated cams mounted at the sides of said member adapted to 105 project inwardly into engagement with the sides of said conduit to thereby retain said member and said capping against accidental displacement, and means whereby said cams may be disengaged from the sides of said 110 conduit to permit of the removal of said member.

9. A device for clamping the cover of a container in position thereon, said device comprising top and side walls and being 115 open at its bottom and ends, housings provided in said side walls, and cams pivotally mounted in said housings in such wise as to rock inwardly by gravity.

10. A fastener of the type described, comprising a shoe having side walls and open at its top and ends, and a clamping member having side walls and open at its bottom and ends, said clamping member being adapted to fit over said shoe and being provided with 120 gravity actuated means adapted to frictionally engage with the side walls thereof to retain said fastener in operative position. 125

11. The combination with a conduit comprising a trunk member and a capping there- 130

for, of a shoe adapted to receive said trunk member, a substantially vertical groove in one wall of said shoe, a clamping member adapted to embrace said shoe and said capping, and means carried by said clamping member adapted to project into said groove to clamp said capping firmly in position on said trunk member and to prevent accidental vertical or longitudinal displacement of said clamping member. 10

In witness whereof I hereunto subscribe my name this 13th day of August, A. D. 1917.

JOHN M. FITZ GERALD.
